DESIGN FOR A SCOURING BRUSH

Melvin H. Partridge, New Rochelle, N. Y., assignor to Ox Fibre Brush Company, Inc., New York, N. Y., a corporation of Delaware

Application December 1, 1939, Serial No. 88,605

Term of patent 7 years

To all whom it may concern:

Be it known that I, Melvin H. Partridge, a citizen of the United States, residing at New Rochelle, in the county of Westchester and State of New York, have invented a new, original, and ornamental Design for a Scouring Brush, of which the following is a specification, reference being had to the accompanying drawing, forming part thereof.

Figure 1 is a top plan of a scouring brush showing my new design; Fig. 2 is a side elevational view of the brush, and Fig. 3 is a bottom plan view thereof.

I claim—

The ornamental design for a scouring brush, substantially as shown.

MELVIN H. PARTRIDGE.
